POCKET BOOK COVER

Awrey Ecclestone, St. Genevieve de Pierre Fonds,
Quebec, Canada

Application August 4, 1958, Serial No. 753,036

3 Claims. (Cl. 281—34)

The present invention relates to the manufacture of book covers or temporary bindings for books.

At the present time, the paper-backed or pocket book is becoming more and more popular and publishers are printing not only current fiction in this manner but also famous works, technical books and the like which the buyer will tend to retain and possibly place with his standard bound books.

Unfortunately, while the printing and plates of these paper-backed books are usually of excellent quality, the covers in many cases do not lend themselves to installation in a permanent book collection, both from the point of appearance and resistance to handling.

The present invention recognizes this problem and aims to provide an adjustable book cover assembly or temporary binding that is adapted to be quickly and easily mounted on a standard paper-backed book and which will give a book of this nature an appearance and quality equal to those of a standard bound volume.

Accordingly, the invention comprises an adjustable book cover assembly adapted for use in the binding of paper-backed books which consists of an outer cover of suitable flexible material which can be adjusted to suit books of varying thicknesses and an inner flap cover which provides additional reinforcement and a means of placing a title on the exterior of the cover. More specifically, the outer cover is of substantially rectangular outline and is made preferably of a single piece of material folded on itself at each side to provide opposed inwardly facing pockets or flaps adapted to receive at least a portion of the top and bottom covers of the book to be bound. The central portion of this outer cover is provided with a pair of transverse spaced apart indentations or perforations of a length sufficient to span the width of the thickest pocket book and these indentations are adapted, when pressure is applied, to open and provide narrow slits.

The inner flap cover is also preferably a single piece of material, for example a piece of paperboard or cardboard, which is of a size adapted to fit within the outer cover with the side marginal portions fitting snugly within the outer cover side flaps. This inner cover is provided with indicating lines adapted to provide a reference for the location of the book to be bound, and an upper central portion so marked is adapted to be slit inwardly to provide a tongue portion adapted to receive the title of the book on the surface against the outer cover. When the cover is assembled this tongue portion of the inner cover is inserted through the slits in the outer cover so that the portion bearing the title is exposed.

Having thus generally described the nature of the invention, particular reference will be made to the accompanying drawing illustrating a preferred embodiment thereof, and in which:

Figure 1 is a view in perspective elevation of a paper-backed or pocket book bound with the book cover assembly of the invention.

Figure 2 is a somewhat diagrammatic view in perspec-

2

tive elevation of the outer cover and inner flap elements of the construction of the invention in superimposed relationship with the book shown in chain lines.

Figure 3 is a view in plan of a preferred one-piece blank from which the outer cover is made.

Figure 4 is a view in plan of the inner flap cover.

Figure 5 is an enlarged detail view of the upper central portion of the inner flap to show the folding over of the marginal edges of the title-bearing portion.

Figure 6 is a sectional view of the construction shown in Figure 1 along the line 6—6.

Figure 7 is a sectional view of the construction shown in Figure 1 along the line 7—7.

Figure 8 is a sectional view of the construction shown in Figure 1 along the line 8—8.

With particular reference to Figure 2 of the drawings, a preferred construction of a book cover assembly in accordance with the invention consists of the combination of an outer cover 10 and an inner flap or cover 12 which are mounted over the usual covers A and B of a standard paper-backed or "soft bound" book, as shown in Figure 1.

The outer cover 10, which is preferably made of a flexible plastic material, is preferably formed from a one-piece blank, as shown in Figure 3. The outer side marginal portions 14, 16 are folded over and secured along the top and bottom margins, for example by known heat sealing processes, to provide inwardly facing side flaps 18, 20.

Prior to the folding of the flaps 18, 20 and preferably during the production cutting of the blank, the marginal portion 14 is slit, as indicated at 15, providing the portion 17 which, when the side flaps are connected, provides an integral book mark. At the same time the central portion of the blank is embossed or partially perforated to define the break-out slits 30a, 30b. Preferably, these slits are defined by the embossing or perforating so that they can be readily opened out when the cover is utilized but remain closed to avoid catching or deformation when the covers are handled or packed for shipping prior to their use.

The inner flap or cover 12 is also made of a one-piece blank of material, preferably of a less flexible nature than the outer cover, for example paperboard or cardboard, and is provided on one surface with indicating lines or perforations 13a, 13b, defining an area 15 corresponding in location to the spacing between the slits 30a, 30b on the outer cover 10. The center line of the inner flap 12 is also indicated by a suitable line or lines 31 to provide a means of accurately locating the book to be bound.

To assemble the cover of the invention, the book to be bound, for example as indicated at C in broken lines in Figure 2, is placed over the inner flap 12 with the center of its spine on the line 31. A line is then drawn or scored along both sides of the book from top to bottom to indicate the width on the inner flap 12. The title, author, or any other desired identifying mark is then written or typed on the area 15 of the flap 12. The flap 12 is then cut along a pair of lines or perforations 32 down to the bottom line 13b defining the area 15 and inwardly at each side along the line 13b to the mark delineating the width of the book. The inner flap 12 is then turned over and the edges of the portion 19 defined by the newly cut slots folded inwards along the drawn lines, as shown in Figure 5.

The transverse slits 30a, 30b are opened up and the inner flap 12 placed on top of the cover 10 with the portion 19 inserted into the slit 30b up and back through the top slit 30a, as shown in Figure 6. The side portions of the inner flap 12 are then placed in the side flaps 18, 20 of the outer cover pushing the inner flap well up to the top of the cover 10. The book C is then placed on top

of the inner flap 12 and the top and bottom covers inserted in the cover side flaps 18 and 20, as shown in section in Figure 8. The end result is a permanently bound attractive book with a neat title card well suited for insertion in a library or the like.

As will be appreciated by reference to the preceding description and the accompanying drawings, book cover assemblies in accordance with the invention can be made in any size although it has been found that a standard size of about 10" x 7½" when opened, as shown in Figure 2, will suit most paper-backed books of the "pocket" size. The finish and color of the outer cover can also be varied as desired since, as is well known, the flexible type plastic sheet preferred for this purpose is available in many finishes and colors.

I claim:

1. An adjustable book cover assembly adapted for use in the binding of paper-backed literature, comprising in combination, an outer book cover of flexible material having an overall rectangular outline with inwardly facing book cover receiving flaps at each side of the inner surface, said outer cover having a central portion provided with indentations defining a pair of spaced apart transverse slits; and an inner cover flap of correspondingly rectangular outline having side marginal portions fitting snugly within said outer cover side flaps at each side, a central portion of said inner cover flap corresponding in location to said outer cover central portion being pro-

vided with parallel slits defining a title-bearing area inserted through said outer cover transverse slits to locate a portion equal to the spacing between said slits exteriorly of said outer cover so as to expose a title located thereon.

5 2. An adjustable binding for a paper-backed book, comprising in combination, an outer cover of flexible material having opposed inwardly facing side flaps adapted to receive the forward marginal edges of the usual covers of the book to be bound, a pair of spaced transverse slits in the central portion of said outer cover adapted to engage the spine of said book; and an inner cover flap having side marginal portions fitting snugly within said outer cover side flaps and a central portion provided with an upper section defined by spaced apart slits and constituting on the inner surface a title-bearing area, said inner cover central upper section extending through one of said outer cover slits, along the exterior of said outer cover, and back through the other of said outer cover slits to locate said title-bearing area exteriorly of said cover.

10 3. A temporary binding for a paper-backed book, as claimed in claim 2, wherein side marginal portions of said inner flap central upper section defined by said slits are folded inwardly at each side prior to their location through said outer cover slits.
